UNITED STATES PATENT OFFICE.

EDWARD A. BANSCHBACH, OF CHICAGO, ILLINOIS.

STAND.

1,219,220.

Specification of Letters Patent. Patented Mar. 13, 1917.

Application filed August 23, 1915. Serial No. 46,790.

To all whom it may concern:

Be it known that I, EDWARD A. BANSCHBACH, a citizen of the United States, residing at Chicago, in the county of Cook and 5 State of Illinois, have invented certain new and useful Improvements in Stands, of which the following is a description.

This invention relates to a stand and an attachment for a stand for supporting machines, such as typewriters or adding machines, so that they are accessible to an operator in a sitting posture.

The principal object of the invention, therefore, is to provide an improved stand 10 or an attachment for existing stands, by means of which the above object may be accomplished. Other objects will appear hereinafter.

In the drawings, Figure 1 is a perspective 20 of a stand constructed in accordance with the principles of my invention and used to support an adding machine; Fig. 2 is a side elevation of a portion of the stand and the machine; and Fig. 3 is a perspective of the 25 front support.

It is difficult to support an adding machine in such a manner that an operator can use the machine while in a sitting posture, for in the common type of stands employed 30 in connection with such a machine, there is a support for the bottom of the stand at the front and rear, which, if sufficiently high to allow the knees of the operator to be placed directly under the front of the machine, is 35 so high that the operator cannot reach the rolls and operating mechanism at the back of the machine, so that up to the present time it has been almost the universal practice to provide a stand or support for the adding 40 machine which necessitates the user operating it in a standing position. In places where the machine is used continuously, this becomes very tiresome, and if a proper stand is provided, the machine can be operated 45 just as well with the operator in a sitting posture. This invention relates to an attachment for the existing type of stands or an entirely new stand in which the machine is supported in such a manner that the knees 50 of the operator are positioned at the sides of the machine, which allows the body to be close to the end of the machine, permitting the operator to reach every part of the ma-

chine for convenient manipulation and operation.

Referring now more particularly to the drawing, the reference numeral 4 designates generally each of the two lateral supporting members of the stand which are preferably constructed of tubing, and these lateral supports are connected at the rear with a cross-brace 5, and at the bottom with a brace 6. A rear supporting bar 7 is also secured to the lateral supports 4 at the rear thereof, and this bar is usually employed to support 60 the rear end of an adding machine 8, or of course any other machine for which the stand is designed.

At the front of the stand is a yoke 9 having bent ends 10 which are designed and 70 adapted to be hooked over the sides of the frames 4 at the front thereof, and with a depending portion 11 which fits under the front of the machine and is of a width slightly greater than the width of the machine. A certain type of machines has a motor 12 for operating the machine, and each 75 motor usually has an extension 13 projecting from the side and rear thereof so that in placing the machine on the stand, or removing it therefrom the machine must be carefully lifted at the rear and practically unhooked from the bar 7. In order to remove the machine from the front of the stand, it is necessary only to raise the front of the 80 machine slightly and to slip the yoke 9 from the stand; whereupon the front of the machine may be lowered and the machine easily disconnected or disengaged from the bar 7 at the rear. In placing the machine on the 85 stand, this operation is reversed, the machine first being hooked over the bar 7 and then the yoke 9 being placed in position. It is obvious that with the present construction, it is not necessary to raise the entire machine bodily in an upward direction and the 90 machine can be more easily handled by simply raising one end at a time.

If desired, a locking device 14 may be provided for holding the yoke 9 in place on 100 the frame by inserting it through the hooked portions 10, and the bar 7 may be raised or lowered by means of pins 15 inserted through openings 16 of the frame. The 105 height of the front of the machine may be determined by the depth of the yoke, and

o gaging said supports to hold up the front of
t a machine and to leave an unobstructed space
y in the stand at the sides of the machine above
e the plane of the base thereof for the knees of
s an operator.

5. A yoke for supporting the front of a
machine, consisting of a depending portion
for setting the machine, with lateral exten-
sions to extend over the knees of an operator,
and hooks at the extremities of the exten-
sions by which the yoke is supported.

6. The combination with a machine to be
supported at a distance from the floor, of a
stand therefor comprising a fixed support
for the rear of the machine, and a removable
support for the front of the machine which
leaves an unobstructed space at each side of
the machine between it and the stand for the
knees of an operator in sitting posture to
enable him to sit close to the machine.

7. The combination with a machine of the
class described, of a stand therefor having a
support extending under the rear of the ma-
chine, and a removable yoke supported by
the stand above the base of the machine, but
having a depending portion which holds
the front of the machine with its base below
the upper portion of the yoke leaving a space
between the depending portion and each side
of the stand for the knees of an operator.

8. The combination with a machine, of a
supporting stand therefor comprising spaced
lateral supporting members and a support
for the rear of the machine, and means de-
pending from the said members to support
the front of the machine at a level below that
of the said members, and to hold the front
of the machine at spaced distances from both
of the members so that the knees of an opera-
tor in sitting position may be placed between
the machine and said members.

9. The combination with a machine sup-
porting stand having spaced lateral supports
and a rear machine support, of a front sup-
porting yoke having a depending portion
with lateral extensions engaged at the ex-
tremities by the lateral supports, and a lock-
ing device to hold each end of the yoke in en-
gagement with the lateral support.

10. The combination in a machine sup-
porting stand which has spaced lateral sup-
ports, of a support for the rear of the ma-
chine, and a movable front support having
a depending central portion with lateral ex-
tensions on each side engaged at the extre-
mities by the said lateral supports of the stand,
leaving a space between the depending por-
tion and the lateral stand supports into
which the knees of the user may be placed to
bring the body of the user close to the front
of a machine.

11. The combination of a machine to be
supported at a distance from the floor, and
a stand therefor comprising spaced lateral
supports and a yoke having a central de-

yokes of various depths may be provided to
suit different conditions and operators. It
is also contemplated that the rear bar 7 ma-
be dispensed with, simply using two or mor
yokes 9 to support the machine, or the yoke
may be made continuous or in sections fo
the same purpose.

It is obvious, of course, that the appli-
cant's yoke may be used as an attachmen
for existing stands, the only necessity bein
that the side supports be spaced apart a sui-
cient distance to permit the knees of an op-
erator to be placed between the machine an-
the side supports, and in this connection i
should be noted that the yokes 9 may b
of various widths to support various size
of machines and to be applicable to variou
widths of stands, the main object being t
provide a support for the front of the ma-
chine which will not obstruct the knees o
an operator in any way, so that the operato
can move close to the front of the machin
for manipulating the machine while in
sitting posture.

It is obvious that the same result may b
accomplished by fastening extending mem-
bers to the front of the machine, or by sup-
porting the front of the machine from be-
neath by bars or a sub-base construction. A
cross bar may also be used to connect th
two lateral supports 4 at the front with de-
pending members or connections, to engag
and support the front of the machine.
These modifications, however, are believed t
be within the scope of the present inventio
and it is thought unnecessary to specificall
illustrate them.

I claim:

1. The combination of a machine stand
and a yoke-shaped support having side ex-
tensions with hooks at the extremities whic
engage over the side rails of the stand leav-
ing a space between the side rails and th
yoke for the knees of a user and for spacin
and holding the side rails of the stand i
spaced position.

2. In a machine-supporting stand, a sup-
porting yoke having a depending portion t
seat the machine and lateral extending por-
tions to provide an unobstructed space belo
the extending portion at the sides of the de-
pending portion above the lower level there
of for the knees of on operator.

3. The combination with a machine to b
supported, of a stand therefor having spaced
lateral supports, and a front support for th
machine having extremities which engag
the supports and an intermediate depending
portion to seat the machine, leaving a spac
at each side of the depending portion be-
tween the machine and the lateral suppor
above the plane of the base of the machin
for inserting the knees of an operator.

4. The combination of a stand having up
right lateral spaced supports, and a yoke en

pending portion into which the front of the machine is placed, and lateral extensions with hooks at the extremities which are placed over the lateral supports, the extensions being of sufficient width so that the knees of a user may be placed between the machine and the lateral supports, and a fastening device to connect each hooked extremity with the lateral support which it engages.

In testimony whereof I have signed my name to this specification, in the presence of two subscribing witnesses, on this 21st day of August A. D. 1915.

EDWARD A. BANSCHBACH.
